Date accessed: Jun. 13, 2014.*Primary Examiner* — Richard E Chilcot*(74) Attorney, Agent, or Firm* — McAndrews Held & Malloy, Ltd.**(57) CLAIM**

The ornamental design for a display screen or portion thereof with graphical user interface, as shown and described.

DESCRIPTION

FIG. 1 is a front view of display screen or portion thereof with graphical user interface showing the new design; and, FIG. 2 is a front view thereof, in which a mobile device in broken lines is provided to illustrate an example environment. The broken line showing of the mobile device in FIG. 2 represents environmental subject matter and forms no part of the claimed design.
